UNITED STATES PATENT OFFICE.

CAMILLO SISMONDI, OF TURIN, ITALY.

SEAL FOR BAGS, &c.

1,168,830.

Specification of Letters Patent. Patented Jan. 18, 1916.

Application filed November 29, 1912, Serial No. 734,126.

To all whom it may concern:

Be it known that I, CAMILLO SISMONDI, notary, of Via Ormea 34, Turin, Italy, have invented certain new and useful Improvements in Seals for Bags, &c., of which the following is a full, clear, and exact specification.

This invention relates to means for retaining the ends of cords which are secured around packages for preventing the opening thereof without necessitating either the cutting of the cords about the packages or the mutilation of the means which retain the ends of said cords. In the event that either of these latter methods have been resorted to gain entrance to the packages, it will be readily apparent, that it would be comparatively easy to detect that they had been tampered with.

Referring more particularly to the accompanying drawings wherein:

Figure 1 is a perspective view of the means wherewith I accomplish the foregoing objects. Fig. 2 is a cross section of my device as illustrated in Fig. 1. Fig. 3 shows the means which retains the ends of the cord. Fig. 4 shows same before being bent into operative position. Fig. 5 illustrates my seal with one end of the cord, to be secured, passed therethrough; and Fig. 6 shows my seal in applied position.

a represents a casing for the seal proper, said casing being provided at its upper ends with openings *b* and *c*. Arranged within the interior of the casing *a* is what might be termed the seal proper *e* which comprises a strip of metal bent so as to be longitudinally U-shaped in cross section, said strip having its two longitudinal edges preferably serrated as illustrated in Figs. 3 and 4. This strip is bent to conform with the interior of the casing *a* and inserted therein in such a manner that the serrated edges thereof are directed toward the longitudinal axis of the casing. It will be noted that the casing *a* is provided at its upper end with a projection *d*, the purpose of which will hereinafter more particularly be set forth.

My device is put to practical use as follows: After the cord has been sufficiently tightened around the neck of the package or bag, it may be placed on the top of the cas-

ing *a* whereupon the lug *d* may be turned down thereby clamping the cord *g* in place, until it shall become convenient to permanently seal the package or bag *f*. When it is desired to seal the package the terminals of the cord *g* are passed through the openings *b* and *c* respectively. A blow is then delivered to the exterior of the casing *a*, by hammer or other suitable means, thereby crushing the exterior of the casing *a*, to a certain extent, and as the sealing member *e* is arranged within the casing *a* thereby also crushing this latter member and forcing the serrated edges of the member *e* to engage the ends of the cord *g*, thereby retaining the same within the casing *a* and making the removal thereof therefrom practically a matter of impossibility.

Having thus described my invention what I desire to claim is:

In combination, a cord, a seal comprising a rectangular body of hollow compressible material open at one end, said body having an opening at its opposite end to receive one end of the cord aforesaid for connection with said body upon preliminary compression of the same, the body also having a second opening adjacent to the last-mentioned opening to receive the other end of the cord preliminary to subsequent compression for connecting the last-mentioned cord end with the seal body, a projection extending adjacent to the second opening aforesaid and adapted to be folded against the body for temporarily clamping the last-mentioned cord end thereagainst, and a toothed clamping member disposed within the body and comprising a strip of relatively hard material bent into spiral form and inserted in the open end of the body, the edges of the open end of said body being adapted to retain the clamping member therewithin, whereby to seal the cord within the body upon final compression of the same.

In witness whereof, I have hereunto signed my name in the presence of two subscribing witnesses.

CAMILLO SISMONDI.
